US0D1059951S

(12) **United States Design Patent** (10) Patent No.: **US D1,059,951 S**
 Pamplin et al. (45) Date of Patent: ** Feb. 4, 2025

(54) **PORTABLE BLENDER JAR**(71) Applicant: **BlendJet Inc.**, Benicia, CA (US)(72) Inventors: **Ryan Michael Pamplin**, San Juan, PR (US); **William Faxon Gordon**, Petaluma, CA (US)(73) Assignee: **BlendJet Inc.**, Benicia, CA (US)(**) Term: **15 Years**(21) Appl. No.: **29/857,924**(22) Filed: **Oct. 26, 2022**(51) LOC (15) Cl. **31-00**

(52) U.S. Cl.

Primary Examiner — Jennifer L Rempfer*Assistant Examiner* — Kendra L Hebel(74) *Attorney, Agent, or Firm* — Esplin & Associates, PC**CLAIM**

The ornamental design for a portable blender jar as shown and described.

DESCRIPTION

FIG. 1 is a perspective view of a portable blender jar showing the new design;

FIG. 2 is a front view thereof;

FIG. 3 is a side view thereof; and,

FIG. 4 is a rear view thereof.
